FOLDABLE LINE-DRYING REEL

Filed July 28, 1949

INVENTOR.
WALTER D. HENGST

BY *Woodbury*
ATTORNEY

the invention relates to a reel of the type used by fishermen to dry their lines on, as distinguished from the usual fishing reel that is mounted on a rod and used to pay out and draw in the line while fishing.

It is an object of the invention to provide a drying reel of open construction and sufficient size to support a substantial amount of line in such condition as to permit free circulation of air therethrough, while being readily foldable into a compact space when it is not in use.

Another object is to provide an efficient drying reel of the folding type that is of such construction that it can be produced at low cost.

Other more specific objects and features of the invention will be apparent from the following description of the invention with reference to the drawing, in which:

Fig. 1 is a front elevational view of a reel in accordance with the invention, shown expanded ready for use;

Fig. 2 is an end elevational view of the expanded reel, looking at the right end in Fig. 1;

Fig. 3 is a detailed view, partly in section, taken in the plane III—III of Fig. 1;

Fig. 4 is a detailed section taken in the plane IV—IV of Fig. 1;

Fig. 5 is a detailed section taken in the plane V—V of Fig. 2;

Fig. 6 is a front elevation showing the reel being folded; and

Fig. 7 is a front elevation showing the reel fully folded.

Referring to Fig. 1, the reel has a sheet metal base 10, the ends 11 of which are turned up to hingedly support a pair of wire standards 12 which have at their upper ends bearings 13 for rotatably supporting an axle 14, the latter carrying a pair of hubs 15 each of which hingedly supports four spokes 16. Each pair of juxtaposed spokes at opposite ends of the axle hingedly support a bar 17. The four bars 17, extending parallel to the axle 14 and being symmetrically disposed thereabout, constitute the line-supporting elements upon which a line to be dried is wound.

Referring now to the details of construction, each of the standards 12 consists of a single piece of stiff wire of U configuration, the cross member 18 of the U extending through apertures provided therefor in lugs 19 bent at right angles from the sides of the upstanding ends 11 of the base 10, for hingedly supporting the standards. Each standard is spring-urged into erect position by a torsion spring 20 wound around the

ends of the lugs 19 and the ends of the U configuration being bent at right angles to the U configuration and being hinged to the respective ends 11 of the base 10. The standards 12 are hinged to the base 10 at the points where the lugs 19 are bent at right angles, and the standards 12 are hinged to the axle 14 at the points where the bars 17 are hingedly supported by the standards 12.

The axle 14 is a square axle having a central longitudinal bore 21 of square cross-section, and the axle 14 is supported by a pair of bearings 13 which are rotatably mounted on the hubs 15.

The hubs 15 are each provided with a pair of journals 15a formed on the outer ends of the hubs 15, the outer ends of the hubs 15 being upset, as indicated at 15b in Fig. 5, to retain the bearings 13 on their journals.

The axle 14 is square in cross-section, and the hubs 15 have square central passages therethrough as shown in Fig. 4, so that they are forced to rotate with the axle, while being longitudinally slidable thereon. Escape of the axle from the hubs is prevented by pins 22 in the axle adjacent opposite ends thereof.

As previously indicated, the hubs 15 each support the four spokes 16 in radially extending position, and to this end, each hub has four bifurcated arms 15d between which the inner ends of the spokes are pinned, by pins 15e. To maintain the spokes at each end in a plane perpendicular to the axle 14, the hubs 15 have inner walls 15f (Fig. 5), which contact the spokes and prevent them from swinging inwardly from the perpendicular plane.

The spokes 16 are shown (Fig. 2) as folded from narrow strips of sheet metal, with the fold at the outer end. For a distance adjacent their outer ends the two folds 16a and 16b are spaced apart the width of the bars 17, and the latter are extended between the folds and pinned thereto by hinge pins 16c. Adjacent their inner ends, the two folds 16a and 16b lie against each other to minimize the spacing between the bifurcated arms 15d of the hub 15.

To rotate the reel, a hand crank is provided on the right end of the axle 14, the arm 25 of the crank having a slot 25a (Fig. 2) whereby it can be slipped over the end of the square axle 14, and be removably retained on the shaft by a link 26 having an eye 26a (Fig. 1) at one end that engages the slot 25a, and having a pin portion 26b that extends through a transverse hole provided therefor in the axle 14. During winding, the handle is prevented from slipping off the end of the axle by the link 26.

FOLDABLE LINE-DRYING REEL

Walter D. Hengst, North Hollywood, Calif.

Application July 28, 1949, Serial No. 107,243

5 Claims. (Cl. 242—111)

1

This invention relates to small portable reels for use by fishermen to dry their lines on, as distinct from the usual fishing reel that is mounted on a rod and used to pay out and draw in the line while fishing.

An object of the invention is to provide a drying reel of open construction and sufficient size to support a substantial amount of line in such condition as to permit free circulation of air therethrough, while being readily foldable into a compact space when it is not in use.

Another object is to provide an efficient drying reel of the folding type that is of such construction that it can be produced at low cost.

Other more specific objects and features of the invention will be apparent from the following description of the invention with reference to the drawing, in which:

Fig. 1 is a front elevational view of a reel in accordance with the invention, shown expanded ready for use;

Fig. 2 is an end elevational view of the expanded reel, looking at the right end in Fig. 1;

Fig. 3 is a detailed view, partly in section, taken in the plane III—III of Fig. 1;

Fig. 4 is a detailed section taken in the plane IV—IV of Fig. 1;

Fig. 5 is a detailed section taken in the plane V—V of Fig. 2;

Fig. 6 is a front elevation showing the reel being folded; and

Fig. 7 is a front elevation showing the reel fully folded.

Referring to Fig. 1, the reel has a sheet metal base 10, the ends 11 of which are turned up to hingedly support a pair of wire standards 12 which have at their upper ends bearings 13 for rotatably supporting an axle 14, the latter carrying a pair of hubs 15 each of which hingedly supports four spokes 16. Each pair of juxtaposed spokes at opposite ends of the axle hingedly support a bar 17. The four bars 17, extending parallel to the axle 14 and being symmetrically disposed thereabout, constitute the line-supporting elements upon which a line to be dried is wound.

Referring now to the details of construction, each of the standards 12 consists of a single piece of stiff wire of U configuration, the cross member 18 of the U extending through apertures provided therefor in lugs 19 bent at right angles from the sides of the upstanding ends 11 of the base 10, for hingedly supporting the standards. Each standard is spring-urged into erect position by a torsion spring 20 wound around the

In Fig. 1 the reel is shown mounted on a table top 27, to which it is detachably clamped by a pair of spring wire clamps 28, which are of approximately U shape. The end of one leg 28a (Fig. 2) of each clamp is extended through an eye 29a in the upper end of a pin 29 that extends through an aperture provided therefor in the base 10 and is upset on the underside to prevent its escape but not prevent its rotation. The end of the clamp arm 28a beyond the eye 29a is bent as shown at 28b to prevent escape of the arm from the eye. The free end of the other arm 28c of the clamp 28 may be bent into a ring 28d for engagement by the operator's finger to facilitate the placing and removal of the clamps.

When not in use the reel can be folded into a compact form by simply forcing the hubs 15 toward each other along the axle 14, the structure folding as shown in Fig. 6 into the form shown in Fig. 7. The folding movement may be conveniently started by pressing the standards 12 toward each other, and completed by pressing the bars 17 together and toward the base 10. To lock the reel in folded position against the opening force exerted by the torsion springs 20, a latch 30 is provided on the outer face of each end member 11, which latches are rotated to engage the ends of the axle 14. The ends of the axle are supported laterally, when in folded position, by a slot 11b in the upper edge of each end member 11. The handle is folded as shown in Fig. 6 prior to collapse of the standards, so that it lies on top of the axle. The clamps 28, after being disengaged from the table top, are rotated on the pins 29 to lie flat on the base 10, as shown in Figs. 6 and 7. To center the axle longitudinally when the device is folded, a stop 31 is preferably provided at the center of the axle, which is engaged between the two hubs 15 when the device is folded.

A reel as disclosed, in which the bars 17 are ten inches long and have a radius of about five inches, will support many hundreds of feet of fishing line in loose relation for rapid drying, and can be folded into a space one and five eighths inches wide, one and seven eighths inches high, and twelve and one half inches long.

An advantage of the construction is that there are no loose parts to become lost, every part being connected to the rest, both in the open and closed positions of the device.

Another advantage is that the device can be inexpensively constructed because nearly all parts thereof can be made of either sheet metal or wire. Only the hubs 15, bearings 13, and axle 14 must be formed by other methods.

Although for the purpose of explaining the invention, a particular embodiment thereof has been shown and described, obvious modifications

will occur to a person skilled in the art, and I do not desire to be limited to the exact details shown and described.

I claim:

- 5 1. A foldable reel comprising: an elongated base; a pair of standards each hingedly secured at one end to said base for swinging movement between an erect position approximately perpendicular to said base and a folded position adjacent and approximately parallel to said base member; an axle; a pair of hubs slideable longitudinally on said axle; each hub having a bearing rotatably connected therewith, for rotatably supporting said hubs for rotation about the axis of said axle; means hingedly connecting said respective bearings to the other ends of said respective standards for rotation of the bearings with respect to the standards about an axis parallel to the axes of swinging movement of said standards on said base; a plurality of spokes hingedly connected to each hub for swinging movement with respect thereto between positions extending radially from the hub and positions substantially parallel to said axle, the spokes on one hub being juxtaposed to the respective spokes of the other hub; bars extending between each juxtaposed pair of spokes and hingedly connected to the free ends thereof for swinging movement in the plane of these spokes; and means for normally retaining said standards in erect position.
- 10 2. A reel according to claim 1 including spring elements for urging said standards from folded toward erect positions.
- 15 3. A reel according to claim 2 including steps on said base for blocking movement of said standards past erect positions.
- 20 4. A reel according to claim 1 in which each standard consists of a U shaped wire with the bottom of the U hingedly secured to said base, said bearings have external, diametrically opposite recesses, and the free ends of said U shaped wire being angled to extend into said recesses and thereby hingedly support said hubs.
- 25 5. A reel according to claim 1 including cooperating means on said axle and hubs for preventing relative rotation therebetween and maintaining each hub and its spokes in alignment with the other hub and its spokes.
- 30 50
